US0D1028896S

(12) **United States Design Patent** (10) **Patent No.:** **US D1,028,896 S**
(45) **Date of Patent:** **** May 28, 2024**

(54) **DEMAGNETIZATION APPARATUS**

(71) Applicant: **Maurer Magnetic AG**, Grüningen (CH)
(72) Inventor: **Albert Maurer**, Grüt (CH)
(**) Term: **15 Years**
(21) Appl. No.: **29/797,121**
(22) Filed: **Jun. 29, 2021**

Related U.S. Application Data

(62) Division of application No. 35/509,514, filed on Nov. 18, 2019 (U.S. filing date under 35 U.S.C. 384), and having an international filing date of Nov. 18, 2019, now Pat. No. Des. 949,106.
